I. N. MERCER

GRAPPLE

Filed Feb. 8, 1923

G.J. Koenrich
Attorney

UNITED STATES PATENT OFFICE.

IZA N. MERCER, OF WELLSBURG, WEST VIRGINIA.

GRAPPLE.

Application filed February 8, 1923. Serial No. 617,824.

To all whom it may concern:

Be it known that I, IZA N. MERCER, a citizen of the United States, residing at Wellsburg, in the county of Brooke and State of West Virginia, have invented certain new and useful Improvements in Grapples, of which the following is a specification.

My invention relates, in general terms, to 10 grapples for use with cranes, derricks and overhead conveyors, and particularly it is designed to provide a grapple wherein shifting or accidental displacement of the load is prevented through the medium of clamping 15 jaws, one of which is adapted to automatically exact a gripping and positive action commensurate with the weight of the load.

My present invention is an improvement over a companion application, Serial No. 20 551,245, filed April 10, 1922, and consists essentially in the provision of means for facilitating the engagement of a load. It frequently occurs that the material to be lifted and transported is at some distance 25 from the ground and it is therefore desirable to so dispose the various elements of the grapple that the operator will not be required to devote his entire attention to adjusting the apparatus. It is pointed out that 30 a grapple of this type is generally composed of from four to six clamping elements.

The principal objects of my invention, briefly stated, are; first, to provide a grapple the jaws of which are automatically 35 maintained in a positive gripping position with respect to a load through the instrumentality of the load when the same is raised from the ground; second, to automatically hold the sliding jaw in selective 40 inoperative position when the load has been released; and third, to automatically lock the immediate actuating mechanism in inoperative position when the load has been 45 released.

To these and other ends, my invention consists in the construction, arrangement and combination of parts described herein- 50 after, illustrated in the drawings and pointed out in the claims forming a part of this specification.

One embodiment of my invention is represented by way of example in the accompanying drawings, wherein:

Figure 1 is a rear elevation of one of my 55 grapples.

Figure 2 is a side elevation partly broken away to show the catch and

Figure 3 is a section taken on the line 3—3 of Figure 2.

Referring to the drawings wherein like 60 characters of reference designate like or similar parts, (1) designates the frame formed of two spaced apart parallel side beams or uprights (2) and (3), connected at their lower ends by a transverse bar (4). 65 The upper ends of the uprights (2) and (3) are bolted or riveted between plates (5) formed each with opposed wings (6). Upon the lower ends of each of the uprights (2) and (3) are integrally formed beveled teeth (7) which extend outwardly at right angles from the uprights for disposition beneath a 70 load.

The movable element of my grapple consists of a beam (8), arranged for sliding 75 movement between the uprights (2) and (3) and the plates (5). This beam is formed with racked side faces (9) and a racked rear face (10). Upon the lower end of the beam (8) is formed a beveled tooth (11) to cooperate with the teeth (7) to dispose a load therebetween. A suitable guide collar (12) is mounted on the beam (8) to hold the beam securely in position between the uprights 80 (2) and (3).

Secured to the rear plate (5) by means of bolts is a bracket (13) having a centrally disposed U-shaped projection (14) which houses a catch (15) pivotally mounted on a pin (16) disposed through the sides of the 90 projection. The catch (15) is provided with a bent portion (17) for engagement in the racked face (10) of the beam (8). A leaf spring (18) is formed on the upper end of the catch (15) and is seated against the rear plate (5) whereby to constantly force the catch into engagement with the beam (8) and retain the same in immovable position. 95

Pivottally mounted between adjacent wings (6) of the plates (5) are levers (19), on the 100 adjacent ends of which are loosely mounted dogs (20) by means of bolts (21). The dogs (20) are preferably formed with a plurality of teeth which are adapted to cooperate with the racked side faces (9) of the beam (8) 105 when the lever is actuated. Links (22) and

(23) are secured to the dogs (20) by the bolts (21), and to each other, by the pin (24). The link (23) is bifurcated to form a shoulder (25) which receives the rounded face (26) of the link (22).

5 Coil springs (27) are attached to ring-screws (28) on the uprights (2) and (3) and to projections (29) on the opposite ends of the levers (19). The levers (19) are also 10 provided with holes (30) for the reception of chains (31) which are united by a ring (32). A source of power (not shown) communicates with the ring (32).

15 It will be understood that the grapple herein described is but one of a similar group which may be connected by any appropriate means to a source of power. When it is desired to apply my grapple to a load the fixed elements or jaw is allowed to rest on the 20 ground and it is not necessary that there be a slack in the chains (31) or the cable of the derrick. By exerting pressure with the hand on the catch (15) the sliding jaw or beam (8) becomes freely movable and when in 25 approximate position the catch is released to hold the beam immovable. When the sliding jaws are in inoperative position the fixed jaw is forced beneath the load. A slight upward touch given at the union of the links 30 (22) and (23) to break the joint will cause them to assume the position shown in the dotted lines in Figure 1, when the dogs (20) are forced into engagement with the racked side faces of the movable jaw or beam.

35 When the chains (30) are drawn taut the levers (19) will be turned on their pivots and the dogs (20) will be thrust into engagement with the sliding jaw to force the tooth (11) to firmly bind the load. The tension 40 of the chains (31) will be dependent on the weight of the load and the force exerted on the sliding jaw will consequently be proportional to the weight of the load. When the grapple is to be disconnected the load is 45 brought to rest, the springs (27) automatically causing the dogs (20) to be retracted, the catch is manipulated and the sliding jaw may be raised a few "notches" clear of the load. The fixed jaws are then removed from 50 beneath the load and the grapple is in inoperative position, ready for application to another load.

55 When the weight of the load becomes passive the coil springs (27) will automatically withdraw the dogs from engagement with the sliding jaw and will exert their force until the link (22) abuts against the shoulder formed in the bifurcated link (23). The levers will then be held in inoperative position 60 by the links so that when the grapple is suspended free of a load the actuating mechanism will remain clear of the sliding jaw. As a consequence the leaf spring (18) which actuates the catch need only be of sufficient strength to withhold the weight of 65

the sliding jaw and thereby allow it to be retained in a selective position. The catch acting as a ratchet will also prevent any reverse movement of the sliding jaw due to accidental shocks against the tooth (11) and in this way all rattling is eliminated.

If in lowering a load some obstacle may temporarily cause a slack in the chains (31) the jaws will be securely held upon the load through the instrumentality of the catch, 75 and the levers and dogs may resume their function without the grip on the load becoming displaced.

80 While in the foregoing there has been illustrated and described such combination and arrangement of elements as constitute the preferred embodiment of my invention, it is nevertheless desired to emphasize the fact that interpretation of the invention should only be conclusive when made in the 85 light of the subjoined claims.

I claim:

1. A grapple comprising a pair of jaws, one of which is adapted for movement with respect to the other, means for locking the jaws in operative engagement when supporting a load and means for locking the jaws in a selective inoperative position.

2. A grapple comprising cooperating load engaging members, means for actuating one of the load engaging members and means for automatically holding the actuating means in inoperative position.

3. A grapple comprising a pair of jaws one of which is movable with respect to the other, means for actuating the movable jaw and means for holding the movable jaw in a selective relation to the stationary jaw when the actuating means are in inoperative position.

4. A grapple comprising a pair of jaws, one of which is movable with respect to the other, means for actuating the movable jaw, means for retaining the movable jaw in inoperative position, and means associated with the actuating means for holding said actuating means in disengagement from the movable jaw.

5. A grapple comprising a frame formed with load engaging members, plates attached to the frame, a beam movably mounted within the frame and between the plates, means for actuating the beam, a bracket mounted on one of the plates, and a catch carried by the bracket and adapted to engage the beam.

6. A grapple comprising a frame formed with load engaging members, plates attached to the frame, a beam movably mounted within the frame and between the brackets, means for actuating the beam, a bracket carried by the plate retaining means, and a catch pivotally mounted on the bracket, said catch having a spring formed in its upper portion and adapted to act against the

plate whereby to cause the catch to engage the beam.

7. A grapple comprising a pair of jaws one of which is movable with respect to the other, opposed plates mounted on one end of the stationary jaw, actuating levers mounted on the plates for pivoted movement, means connecting the plates and levers for withdrawing the levers from operative position, and means for simultaneously actuating the levers and supporting the grapple.

8. A grapple comprising a pair of jaws, one of which is movable with respect to the other, opposed plates mounted on one end of the stationary jaw, levers pivotally mounted on the plates, dogs carried by the levers and adapted to actuate the movable jaw, cooperating links associated with the dogs, and means for actuating the levers.

9. A grapple comprising a pair of jaws one of which is movable with respect to the other, means for actuating the movable jaw,

plates secured to the free end of the stationary jaw, a bracket having a centrally raised U-shaped portion secured to one of the plates, a pin inserted through the sides of the U-shaped portion, a catch mounted on the pin and a leaf spring carried by the catch and adapted to act against the plate whereby to cause the catch to engage the movable jaw.

10. A grapple comprising a pair of jaws, one of which is movable with respect to the other, plates secured to the free ends of the stationary jaw, levers pivotally mounted on opposite ends of the plates, dogs carried by the levers, cooperating links associated with the dogs and adapted to lock them in disengagement from the movable jaw, springs connecting the plate to the outer ends of the levers, and flexible means connecting the levers with a source of power.

In testimony whereof, I affix my signature hereto.

IZA N. MERCER.
